HOLDER FOR BUCKETS

Henry B. Spencer, Charleston, W. Va., assignor of
one-half to Charles W. Chesley, Charleston,
W. Va.

Application November 8, 1937, Serial No. 173,461

3 Claims. (Cl. 220—96)

This invention is a device for attachment to a bucket, by means of which the latter may be suspended in a normally tilted position.

It is well known that painters working from a ladder usually suspend the paint bucket from a rung of the former. It has been observed that because of the position that the bucket normally occupies while in a vertically suspended position, there is hardly sufficient space between the rungs of a ladder for the painter to get the brush into and out of the bucket, and it is also rather difficult as the brush is being withdrawn from the bucket, to efficiently wipe off any excess paint taken up by the brush.

One of the objects of the present invention is to overcome the above-mentioned objections by providing a simple device which may be readily connected to and disconnected from a bucket and its supporting bail, and so constructed and arranged that said bucket may be normally held in an inclined or tilted position while suspended by the bail from a rung of a ladder or other overhead support, with the open portion of the bucket directed toward the workman. A further object is to provide a holding device having a portion so constructed and arranged as to be detachably anchored to a portion of the bucket and also having a hook-like extremity capable of engaging the bail of the ladder adjacent to the pivotal connection of the bail with the body of the bucket, so that relative pivotal movement of the bail and bucket is normally prevented during such engagement, and without rendering the bail useless so far as its normal suspending functions are concerned.

The invention will be hereinafter fully set forth and particularly pointed out in the claims.

In the accompanying drawing:

Figure 1 is a side elevation of a typical bucket with the invention applied thereto, but disengaged from the bail of the bucket. Figure 2 is a similar view taken at right angles to Figure 1. Figure 3 is an elevation similar to Figure 1 showing the holding device engaged with the bail of the bucket and the latter disposed in tilted position. Figures 4 and 5 are enlarged vertical elevations taken at right angles to each other, showing the holding device detached from the bucket.

Referring to the drawing, 10 designates a bucket of any suitable material, but for purposes of illustration, a typical metal paint-bucket is disclosed, the same having bosses 11 extending outwardly therefrom at diametrically opposite positions, each boss being provided with a central

opening 12. The bucket is provided with the usual bail 13, which has its ends inturned and pivotally engaging the bosses 11, the extremities of the bail ends being inserted into the openings 12.

The holding device H of the present invention is preferably made of wire, and it is preferred to construct it of piano wire, because of its inherent strength and resilience, although the invention is not limited in this particular. Said device consists of a ring-like body portion 15, formed by binding one end of a length of wire into a circle, the extremity of said end portion being provided with a radially offset anchor lug 16. Leading approximately tangentially from 15 the body 15 is a straight arm 17 which is provided with a hook 18 at its upper extremity.

In practice, the ring-like body 15 is of a diameter to fit around and rotatively engage one of the bosses 11, in a manner to permit rotative adjustment of said body, and the offset extremity 16 is sufficiently sharpened to be pressed into the metal of said boss at any position within the range of said rotative adjustment, and in such manner as to prevent rotation of the holder relatively to said boss. As shown in Figure 1, the offset extremity 16 has a fixed engagement with the bail boss 11, but the hook 18 is disengaged from the handle. By moving the arm 17 in a direction tending to wrap the body 15 around the boss, until the hook end has moved past the bail, the hooked end 18 may be engaged with the bail. Thereupon, the device H will be placed under tension just as soon as there is any relative movement of the bail to the right, as viewed in Figure 1. Therefore, upon suspending the bail from an overhead support, the tension of the device under the weight of the bucket and its contents will cause the bucket to assume the angular position illustrated in Figure 3.

The advantages of the invention will be readily understood by those skilled in the art to which it belongs. For instance, while the bucket is suspended from the rung of a ladder, or from some overhead position, the open end of the bucket is directed toward the workman and he has a great deal more space through which to manipulate his brush with respect to dipping it into the paint and wiping off any excess paint. A further advantage is that the device is exceedingly simple in construction and of such a nature that it may be readily attached to paint buckets already constructed, or it may be readily attached to newly manufactured buckets, if desired.

Having thus explained the nature of the invention and described an operative manner of constructing and using the same, although without attempting to set forth all of the forms in which it may be made, or all of the forms of its use, what is claimed is:

1. The combination with a bucket having a bail boss and a bail having one of its ends pivotally connected with said boss, of a holder consisting of a single piece of wire provided with a ring-like portion having at one end an inwardly extended radial projection adapted to fixedly engage said boss at any position around the circumference thereof, the other end of said body being provided with a tangentially disposed arm provided with a hook portion adapted to engage said bail.
2. A device for holding buckets in tilted position while suspended from the bail thereof, said device consisting of a ring-like body portion so

shaped as to rotatively encircle a bail boss on the bucket, said body having its inner end provided with a radially inward projection adapted to fixedly engage said boss at any position around the circumference thereof, the other end of said body portion having means to removably engage said bail.

3. A device for holding buckets in tilted position while suspended from the bail thereof, said device consisting of a ring-like body portion so shaped as to encircle and rotatively engage a bail boss on the bucket, said body having an inwardly projected radial arm provided with a pointed end adapted to fixedly engage the periphery of said boss at any position on the circumference thereof, said body having its outer end provided with a tangential arm terminating with a hook adapted to removably engage said bail.
